Primary Examiner — Kimberly Barnes

(57) **CLAIM**

The ornamental design for a vacuum cleaner hose, as shown and described.

DESCRIPTION

FIG. 1 is a perspective view of a vacuum cleaner hose showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof, showing the vacuum cleaner hose in a curved state;

FIG. 9 is another perspective view showing the separated state of vacuum cleaner hose;

FIG. 10 is another perspective view showing the separated state of vacuum cleaner hose with the hose portion in a curved state;

FIG. 11 is an enlarged view of the vacuum cleaner hose taken from the circle part in FIG. 2; and,

FIG. 12 is an enlarged view of the vacuum cleaner hose taken from the circle part in FIG. 3.

The broken lines in the figures depict portions of the vacuum cleaner hose that form no part of the claimed design.

1 Claim, 12 Drawing Sheets
